OIL DRUM RACK

John W. Sherwood, 806 Pine St., Atlantic, Iowa

Filed Apr. 19, 1965, Ser. No. 84,856

Term of patent 14 years

(Cl. D41—1)

FIG. 5FIG. 6FIG. 7FIG. 8FIG. 1 is a perspective view of an oil drum rack showing my new design with an oil drum, shown in broken lines for illustration only.

FIG. 2 is a front view thereof,
 FIG. 3 is a back view thereof,
 FIG. 4 is a side view thereof,
 FIG. 5 is a side view opposite to FIG. 4,
 FIG. 6 is a top view thereof,
 FIG. 7 is a bottom view thereof, and
 FIG. 8 is a perspective showing a variation of this oil drum rack as to size only.

I claim:

The ornamental design for an oil drum rack, as shown and described.
